UNITED STATES PATENT OFFICE

2,666,930

APPARATUS FOR HANDLING RECUMBENT PERSONS

John E. Lenahan, Cornwall-on-Hudson, N. Y.

Application September 9, 1947, Serial No. 772,911

4 Claims. (Cl. 5-86)

1

This invention relates to apparatus for lifting, transferring and temporarily supporting persons in a reclining position, as disclosed in Lenahan Patent No. 2,404,734, issued July 23, 1946, and more particularly to improvements therein and accessional features of construction whereby persons may also be so handled in a sitting position.

The invention has particular reference to an articulated carrier and a suspension means therefore, wherein the suspension means is utilizable with a mobile platform or carriage interchangeably in place of a pair of members of the type utilizable solely for handling recumbent persons, as in said Lenahan patent for example, whereby recumbent persons may be manipulated into a sitting position and transferred in such position into a conventional chair and from a chair, in sitting position, into a bed and subsequently released into a reclining position.

The invention has further reference to an improved apparatus of the character specified wherein a portion of the mobile carriage or platform is relatively adjustable into any one of a plurality of positions whereby the platform is adapted for passage thereof through narrow doorways, corridors or hallways, as in hospitals and in private homes, or for the storage thereof in a relatively small space.

Objects and advantages of the invention will be set forth in part hereinafter and in part will be obvious herefrom, the same being realized and attained by means of the improved instrumentalities and combinations pointed out in the appended claims.

The accompanying drawings, referred to herein and constituting a part hereof, illustrate one improved embodiment of the invention, and together with the description, serve to explain the principles thereof.

Of the drawings:

Fig. 1 is a perspective view of the complete apparatus, embodying the invention, as assembled and adjusted for transferring a patient in sitting position;

Fig. 2 is a fragmentary detail view in perspective of the anchoring end of one of the angular supporting arms shown in Fig. 1;

Fig. 3 is a fore-shortened detail view in elevation partly in section illustrating the attachment of the anchoring end of an angular supporting arm to the plunger of one of the pedestal jacks;

Fig. 4 is a detail sectional view taken on the line 4-4 of Fig. 3;

Fig. 5 is a view in elevation of the front side

2

of the apparatus as viewed from the left in Fig. 1;

Fig. 6 is a rear view in elevation of a detachable torso and head rest panel per se;

Fig. 7 is a view in perspective of detachable seating panel frame per se;

Fig. 8 is a transverse sectional view in elevation taken on the line 8-8 of Fig. 5 showing a pivoted caster base member fully extended and the opposite member partially extended;

Fig. 9 is a sectional view in elevation, partly fore-shortened, taken on the line 9-9 of Fig. 8;

Fig. 10 is a detail sectional view taken on the line 10-10 of Fig. 8;

Fig. 11 is a detail view in perspective illustrating an open sided hinge bearing as formed at one end of each channel section member;

Fig. 12 is a view in end elevation of the apparatus in general in operative relation to a hospital bed shown in broken lines;

Fig. 13 is a similar view illustrating the apparatus in general in operative relation to a conventional upholstered arm chair shown in broken lines;

Fig. 14 is a top plan view of the apparatus with a pair of cantilever supported scoops of known form, substituted for the suspended carrier in the preceding figures, and in operative relation to a hospital bed shown in broken lines;

Fig. 15 is an end view in elevation of the apparatus in Fig. 14 per se; and

Fig. 16 is a detail view in elevation illustrating an auxiliary extension bracket connected between a plunger and anchoring end of an angular supporting member (Fig. 2) in depending, off-set relation to the plunger.

The principal object of the invention is to provide an improved portable apparatus including interchangeable appurtenances therefor which is readily adjustable with respect to either a bed and a recumbent person therein, or a conventional arm chair and a person sitting therein.

Another object of the invention is to provide an improved portable apparatus, as specified, which is readily adjustable for passage thereof through narrow doorways, corridors or hallways in hospitals or in private homes.

A further object of the invention is to provide an improved portable apparatus of the character specified which by reason of its versatility, compactness and relatively inexpensive construction renders it of especial value in the handling of patients in private homes by a single attendant or nurse.

With the above and other objects in view, the invention resides in the improved features of con-

struction, novel additional parts extending the useful range of the apparatus, and the interchangeable features thereof, combinations and arrangements of the character hereinafter described and claimed.

Briefly described, the invention provides for the use of one or more concave scoops or patient-supports, including handles therefor, which are adapted to be inserted beneath the body of a recumbent person while lying in a bed, as disclosed in the herein identified Lenahan patent. In accordance with the present invention, the free end of each of the scoop handles is provided with an improved anchoring or attaching means as hereinafter described.

The major portion of the apparatus, constructed in accordance with the present invention, comprises a mobile carriage or platform including a pair of pivotally adjustable platform extension members and a pair of pedestal jacks wherein the plungers are each provided with an improved mechanism for receiving the attaching means on each of the above noted scoop handles in interlocking relation or, alternatively, a similar attaching means provided on one end of each of a pair of angular supporting arms adapted for the suspension therefrom of an articulated patient receiving carrier.

Referring to the drawings, the improved apparatus indicated generally at 10, includes a platform 11 comprising a substantially rectangular plate member 12 having a marginal portion 13 turned normal thereto along three sides thereof whereby to substantially impart rigidity thereto.

For a purpose presently to be described, the plate member 12 is further provided with an aperture 14 in each corner portion 15 thereof and, with a relatively small aperture 16 radially adjacent the aperture 14, as clearly shown in Figs. 8 and 9.

As clearly shown in Fig. 11, a relatively heavy U-shape channel member 17, of a length substantially equal to the width of the opposite ends of the plate member 12, is provided with an aperture 18 adjacent each end thereof. A relatively small angle plate 19, apertured as at 20, is set in one end of the member 17, with the respective apertures 18 and 20 in spaced axial alignment, and welded thereto as at 21, one end portion of one side wall of the member 17 being cut away, as at 22, to provide a hinge bearing 23 at one end of and in the plane of the member 17.

Further in accordance with the present invention, a channel member 17, as shown and described in connection with Fig. 11, is secured as by welding, for example, to the underside of the plate member 12, at each opposite end thereof, in abutting parallelism with the turned margin 13 and with the apertures 18 and 20 of the hinge bearing 23 in axial alignment with the aperture 14 in the corner portion 15 thereof.

As clearly shown in Figs. 8 and 9, each of a pair of suitable swivel caster assemblies 24 are directly recessed in the aperture 18, adjacent the end of the channel member 17 opposite its hinge bearing 23, and secured to the plate member 12 by means of suitable rivets 25 or the like extending through the caster base 26 and the plate 12.

As clearly shown in Figs. 8 and 9, a pair of elongated extension members 27, preferably light forgings of channel section, are each provided adjacent one end thereof with a caster assembly 28 suitably pivoted in the underside thereof as at 29.

The opposite end of each extension member 27 is constituted by a solid, semi-circular flat

portion 30 having a central bore 31 therein, and a plurality of relatively small angularly spaced apertures 32 radially adjacent the bore 31.

As thus provided, the end portion 30 of each extension member 27 is positioned in one of the aforesaid hinge bearings 23 and pivotally connected thereto by means of a headed pin bolt 33 including a retaining nut 34 therefor, whereby the extension members 27 are angularly adjustable relative to the mobile platform thus formed.

The platform extension members 27 are adapted to be locked in any one of a plurality of positions by means of a shouldered pin 35 disposed in the aperture 16 provided therefor in the plate 12 of the platform 11 and adapted to be selectively inserted in any one of the apertures 32, provided therefor in the end portion 30, which may be brought into register with the reduced end 36 of the pin 35.

Further in accordance with the invention, a pair of jacks 37, of the hydraulic type for example, are suitably secured on the platform 11 in spaced vertical alignment as by means of the screw bolts 38. Each of the jacks 37 is constituted by a pedestal portion defining a cylinder C closed at its bottom end with a fluid conducting conduit 39 leading into its bottom end and, a cylindrical plunger 40, having end faces square therewith, disposed in each cylinder C for slideable movement relative thereto in known manner.

A horizontally disposed handle bar 41, suitably connected at each end thereof to one of the pedestal jacks 37, as at 42, provides a gripping member whereby the platform may be conveniently guided.

In a manner similar to that shown in the herein identified patent, a hydraulic pump assembly 43, including a fluid reservoir 44, a spring influenced, foot actuatable pump pedal 45 and a relief pedal 46, is suitably secured on the platform 11 between the jacks 37, as by screw bolts or the like 47, and connected to each conduit 39 for pumping a fluid into the cylinders C whereby the plungers 40 are elevated and lowered in known manner.

The upper end of each plunger 40 is counterbored for a short distance, as indicated at 48 in Fig. 3, for the reception of an annular pilot bearing 49 integral with and depending from the bottom face of a clevis block 50 whereby it is secured to its correlated plunger 40 by means of a pin 51 extending through the plunger 40 and the pilot bearing 49 as clearly shown in Fig. 3.

Each of the clevis blocks 50 define a rectangular slot 52 formed by a pair of upstanding, spaced, parallel walls 53 provided with a pair of aligned apertures adjacent one end thereof for the slideable reception therethrough of a locking pin 54 suitably tethered to one wall thereof by an interconnected chain 55.

Further in accordance with the invention each of a pair of angularly formed tubular members, generally indicated at 56, include an anchoring block 57, of rectangular cross section, which is attached to one end portion 58 thereof by means of an interconnecting stub shaft 59, suitably telescoped in and pinned, as at 60 in Fig. 3 to the angular member 56 and anchoring block 57.

Each angular member 56 is further provided with an inclined bracing bar 61 suitably connected to and between its anchoring block 57 and its angularly related portion 62 whereby to maintain the angularly related portions 58 and

62 of each angular member 56 in rigid right angular relation.

As clearly shown in Fig. 2, the uppermost face of each anchoring block 57 is undercut to provide a shoulder or abutment 63 and a hemi-cylindrical groove 64 formed in and across its undercut surface, the opposite or bottom face of each block 57 directly below the groove 64 and including the adjacent end face 65 thereof, being arcuately formed as at 66.

As thus provided, each angular member 56 is detachably secured to one of the clevis blocks 59 and to one of the jack plungers 48 indirectly, by the insertion of its correlated anchoring block 57 in the slot 52 of the clevis block 59 and inserting the locking pin 54, chained thereto, through its aligned apertures whereby the pin 54 is positioned over the groove 64, provided therefor in the anchoring block 57, and in engaging registration with its defining surface as clearly shown in Figs. 3, 4 and 5.

Alternatively, each angular member 56 may be so detachably secured without first withdrawing the locking pin 54 from the clevis block 59. This may be done by inserting the reduced end 65 of its 25 correlated anchoring block 57 in the slot 52, at its end farthest from the pin 54, while tilting the same to bring the groove 64 under the pin 54 and subsequently forcing the adjacent end portion 53 of the angular member 56 into vertical position whereby its anchoring block 57 is wedged under the pin 54 with the plane portion of its bottom face in full parallel engagement with the bottom of the slot 52.

With the angular members 56 secured to the pedestal jacks 37 as hereinbefore described, the free end portions 62 thereof extend in fixed parallel relation at right angles to their vertically disposed portion 58 and beyond one side of the platform 11 but not beyond the platform extension members 27 when in fully extended position as in Fig. 1.

As clearly shown in Figs. 1 and 3, the extended portion 62 of each angular member 56 is provided, inwardly of its free end, with a spacing collar 67 suitably secured thereon as by means of a set screw, pin or the like 68, and at its free end with a finial in the form of a shouldered button plug 69 suitably secured as by means of a set screw, pin or the like 70 as and for a purpose now to be described.

In an alternative arrangement for handling recumbent persons while lying in a bed, the handles 71 of a pair of concave scoops or patient supports 72, as disclosed in the herein identified patent, are each provided, at their free ends, with an anchoring block identical with the anchoring block 57 secured to each of the aforesaid angular members 56.

Accordingly, as clearly shown in Figs. 13 and 14, a similar anchoring block 73 is suitably secured as by welding or otherwise to the free end of each scoop handle 71, in the plane thereof, whereby a pair of such scoops 72 may be utilized with the improved apparatus in lieu of the angular supporting members 56.

For the purpose of supplementing the range of adjustment of the pedestal jacks 37 whereby to accommodate the improved apparatus 10 to a supporting surface lower than a conventional 70 auxiliary offset bracket 14 may be similarly connected to and between each of the clevis blocks 59 and to the anchoring block 57 of each angular member 56 or, the anchoring block 73 on each of the scoop 75

handles 71 in the manner hereinbefore described, and as exemplified in Fig. 16.

Articulated patient carrier

5 As best shown in Figs. 1, 5, 6 and 7, an articulated carrier which is adapted to be readily assembled and disassembled, and to be supported in an assembled condition by the aforesaid angular members 56 in suspended relation thereto, is indicated generally at 75.

10 As shown, the carrier 75 comprises a substantially H-shape base panel B, a head panel H, a foot end frame member F, and a pair of connecting links 76, each provided with an open eye 77 in 15 the opposite ends thereof.

As clearly shown in Fig. 7, the base panel B is constituted by a pair of spaced parallel rails or bars 78 having an open eye 79 formed in each of their opposite ends and, a relatively short panel member 80, having one end margin 81 formed on the arc of a circle and side margins formed substantially normal thereto suitably secured as by welding, for example, intermediate the ends of and to and between the opposite side faces thereof.

20 As clearly shown in Fig. 6, the head panel H is constituted by an appropriately curved plate member 82 having its side margins turned normal thereto for a major portion of its length with a 25 pair of suitably secured button studs 83 spaced longitudinally along the lower end portion of each turned margin. The panel H is further provided on its rear face, adjacent its opposite end, with a pair of elongated hooks 84 each positioned parallel with and at one side margin and appropriately secured as at 85.

The foot end member F is constituted by a pair of flat bars 86 suitably connected in spaced, parallel relation by a pair of spaced rungs 87 intermediate the respective ends thereof. Each bar 86 is provided at one end portion with a pair of spaced button studs 88 and at its opposite end with an elongated hook 89 having its hook portion turned normal to its attached end.

45 As shown in Fig. 5, the connecting link members 76 are formed to a length substantially greater than the length of the rails 78 of the base panel B whereby to receive the button studs 83 and 88, provided respectively on the head panel H and end frame F, in the eyes 77 thereof, the eyes 79 in the ends of the aforesaid rails 78 being likewise adapted to receive the button studs 83 and 88.

50 Finally, an additional link 90, provided with an open eye 91 in each of its ends, is extended between the free ends of the angular members 56 whereby to maintain the extended portions 62 thereof in rigid parallel relation.

55 From an inspection of Fig. 1, it will be clearly apparent that the link members 76, connecting the head panel H and end frame F of the carrier 75, operate to maintain all of the carrier forming sections against relative movement with respect to each other and against swinging movement of the carrier 75 on the extended portions 62 of the angular members 56.

60 Similarly, the collars 67 and end plug 69 in conjunction with the connecting link 90, operate to prevent relative movement of the carrier 75 longitudinally of the extended portions 62 of the angular members 56.

Operation

65 In the manipulation of a recumbent person in a bed, of the hospital or conventional type, into a sitting position for transfer into a chair, for ex-

ample, the plurality of sections and connecting links, constituting the carrier 75 per se, are first assembled beneath and about the recumbent person in the following manner.

The base panel B is first inserted beneath the upper portion of the lower limbs of the recumbent person lengthwise thereof. Subsequently, the head panel H is inserted beneath the torso and preferably beneath a pillow supporting the head, and the eyes 79 of the upper ends of the rails 78 of the base panel B, connected to the lowermost button studs 83 on the head panel H.

Thereafter, the lower ends of the end frame F are placed across the lower limbs of the person, with frame F resting thereon, and the button studs 88, at the said lower ends thereof similarly connected to the opposite eyed ends of the rails 78 of the base panel B.

With the carrier sections B, H and F thus positioned beneath the recumbent person, the head panel H is raised and a pillow or pillows inserted to the rear thereof to hold the same at a substantial angle to the base panel B.

At this point, the links 76 are each connected at one end to the intermediate button studs 82 on the head panel H. The end frame F is now raised substantially normal to the base panel B and the opposite ends of the links 76 attached to the intermediate button studs 88 on the bars 86 thereof.

As thus arranged, only the head and torso of the person are inclined at an angle to the lower limbs and the base panel B.

Subsequently, the mobile platform 11 with the caster extension members 27 and the angular supporting members 56, as in Fig. 1, is now moved to the bed 92 and positioned as shown substantially schematically in Fig. 12.

Assuming that the plungers 49 are in a position of minimum adjustment, the pump 43 is operated to raise the angular members 56 until the extended portions 62 thereof are substantially in the path of the carrier hooks 84 and 89 respectively.

The hooks 84 and 89 of the assemble carrier 75 are now placed on the extended portions 62 of the members 56 and the pump pedal 45 actuated whereby the carrier 75 is raised out of the bed 92 with the person supported in substantially sitting position on the base panel B.

The apparatus 13 is now moved away from the bed 92 to permit change of bed linen, transfer of the person into a chair 93 as in Fig. 13 or, for treatment. At this point it is to be observed that one margin 81 of the supporting surface 80 of the base panel B is arcuately formed to provide clearance for the rectal portion of the person as will be understood.

In the transfer of a person sitting in a chair 93 as suggested in Fig. 13 to a bed as suggested in Fig. 12, the elements constituting the carrier 75 per se, are inserted beneath and about the person in a manner identical with that described above in connection with the bed 92.

While the invention has been illustrated and described with respect to a preferred embodiment thereof, it is to be expressly understood that various changes and modifications may be made therein without departing from the inventive concept underlying the same. Therefore, the invention is not to be limited except as is necessitated by the prior art and the scope of the appended claims.

What I claim is:

1. Apparatus for moving a recumbent person

to a sitting position and transferring him in that position comprising a movable platform having vertically adjustable means connected thereto, carrier supporting means connected to said vertically adjustable means for supporting a carrier at a fixed distance from said vertically adjustable means, a carrier, said carrier comprising a base panel having a surface area sufficient to receive a part of the upper portion of the lower limbs of the person thereon, a head panel having a surface area sufficient to receive the head and torso thereon, an end frame opposite said head panel, means connecting said base panel, head panel and end frame in detachably hinged end to end relation, means detachably connecting said head panel and end frame to maintain said head panel and end frame in a position in which said head panel and end frame extend upwardly from said base panel, and means on the upper ends of said head panel and end frame for detachably connecting said carrier to said carrier supporting means.

2. Apparatus as defined in claim 1 including means for prohibiting the longitudinal movement of the carrier toward or away from the vertically adjustable means.

3. Apparatus for moving a recumbent person to a sitting position and transferring him in that position comprising a movable platform, two jack

30 members spaced vertically on said platform, each of said jacks having vertically adjustable means, an L-shaped angle supporting bar attached to the vertically adjustable means of each of the jack members, the vertical member of each said angle bar being connected to the vertically adjustable means of the respective jack member with the horizontal member of said bar extending laterally of said vertical member, said carrier member comprising a base panel having a surface area sufficient to receive a part of the upper portion of the lower limbs of a person thereon, a head panel having a surface area sufficient to receive the head and torso thereon, an end frame opposite said head panel, upper ends of

40 said head panel and end frame supportingly engaged by the horizontal members of said angle bars, means connecting said base panel, head panel and end frame in detachably hinged end to end relation, means detachably connecting said head panel and end frame whereby said head panel and end frame are each maintained at an angle to said base panel.

45 4. An apparatus as defined in claim 3 including means for preventing longitudinal movement of said carrier on said horizontal members of said L-shaped supporting bars.

JOHN E. LENAHAN.
